DISPENSING APPARATUS AND FAUCET

Thomas A. Nigbor, Whitefish Bay, Wis., assignor
to Howard Mfg. Co., Milwaukee, Wis.

Application March 10, 1941, Serial No. 382,487

14 Claims. (Cl. 225—6)

This invention relates to a dispensing apparatus and faucet for carbonated beverages such as beer.

The invention is concerned with a dispensing mechanism in which a main valve is employed to control the flow of solid beer from the faucet and a supplemental valve is employed to control the character and the amount of the foam which may be discharged from the faucet onto the column of beer previously discharged by the main valve.

The general purpose and object of my invention is to mount both valves within the faucet body and arranged with the supplemental valve discharging through the main valve to simplify the structure and contribute to its compactness for installation and use in a beer drawing system.

A further object of my invention is to have the main valve carry the supplemental valve so that the supplemental valve may remain in closed position during the opening and closing movement of the main valve to prevent the discharge of beer as foam during operation of the main valve.

A further object of my invention is to provide a movable carrier as a support for both valves whereby the operating mechanism for the two valves may selectively open the same.

A further object of my invention is to have the carrier divide the liquid receiving chamber in which the carrier and the respective valves are located into upper and lower sections to provide separate liquid supplies for the respective valves.

A further object of my invention is to produce the foaming by an atomizing action in connection with the supplemental valve, there being an atomizing tube or equivalent restricted passage-way carried by the carrier for the supplemental valve.

A further object of my invention is to locate the seat for the main valve in spaced relation to the discharge opening of the device to vent the gases accumulating at the main valve in advance of the discharge of liquid therefrom to avoid excessive or objectional foaming of the liquid in the initial opening of the main valve.

A further object of my invention is to provide the settling tank or container for the beer or other liquid handled by the dispensing system in advance of the faucet with a check valve device to prevent the expanded gas within the faucet which is out of the influence of the refrigerating action reacting by reason of the in-

creased pressure on the liquid content of the tank to disturb or agitate the same.

A further object of my invention is to partition off the tank at its connection with the faucet and have the check valve in this partition so that any increase in pressure within the faucet will be arrested at the partition and not be communicated to the tank to turbulate its liquid content.

A further object of my invention is to introduce the beer or other liquid from the source of supply into the settling tank preferably adjacent to the bottom of the tank and in a circumferential direction in respect thereto to avoid agitation or turbulence of the beer content of the tank.

The invention consists further in the features hereinafter described and claimed.

In the accompanying drawings illustrating a preferred embodiment of my invention—

Fig. 1 is a side view with parts in elevation and section, respectively, of my improved beverage dispensing apparatus;

Fig. 2 is an enlarged longitudinal sectional view of said apparatus;

Fig. 3 is a cross-sectional view taken on line 3—3 of Fig. 1;

Fig. 4 is a similar sectional view taken on line 4—4 of Fig. 2 to show the actuating shaft for the control valves;

Fig. 5 shows my improved dispensing faucet connected to a direct draw rod with parts in section and elevation, respectively;

Fig. 6 is a sectional view taken on line 6—6 of Fig. 5 to show a detail of construction;

Fig. 7 is a sectional view of a modification to be hereinafter described; and

Fig. 8 indicates the manner in which the foam or collar deposited on the column of beer in a glass or other drinking container by my improved faucet device seals in the gas content of the solid beer.

In Figs. 1 and 2, 1 indicates the front wall of a coil box as commonly used in a beer drawing system of such type. This box is constructed and arranged to hold a supply of water and cracked ice about the coil 2 located within the box to cool the beer in its flow through the coil from the keg (not shown) to a discharging faucet 3 on the front side of the box. In the embodiment shown, I provide a relatively small settling tank or container 4 located within the box 1 in the connection between the coil 2 and the faucet 3 to quiet the flow of the beer to the

faucet for a controlled discharge therefrom. The

tank 4 is supported from the front wall 1 of the box by a shank 5 in the form of a pipe section extending through the box wall and connected at its opposite ends to the tank 4 and the faucet 3, respectively. The conduit section 5 is preferably threaded on its outer side to receive clamp nuts 6, 7 for clamping the shank in place in the box wall 1. A washer 8 is employed with the clamp assembly to close the box opening through which the shank 5 extends.

The top of the tank 4 is closed by a cover casting 9 fitting over the top of the tank as detailed in Fig. 2. This casting is provided with two boss formations 10, 11 both cored to provide passages 12 and 13, respectively. The outlet end 14 of the coil 2 is connected with the passage 12 for the flow of beer from the coil 2 into the tank 4. A clamp nut 15 is employed in the connection as shown. The incoming beer is led to the bottom of the tank 4 through a conduit section 16 located within the tank 4 and connected at its upper end to the passage 12. The lower end 17 of the conduit 16 is at the bottom of the tank 4 and is there fashioned to discharge the beer in a smooth stream circumferentially of the tank 4 and relatively close to its upright cylindrical wall. This is shown in Fig. 3, and the purpose of the arrangement is to lessen, if not completely eliminate, turbulence or agitation of the beer within the tank 4. It is to be understood in this connection that the beer is forced through the system by the gas pressure thereon within the keg from the gas content of the beer as employed for its carbonation and the additional gas pressure which is usually supplied to the keg through its tap rod clamp as in beer drawing systems of the type in question. The tank 4 may be tapered upwardly to aid in quieting its liquid content as shown in Fig. 1.

Also located within the tank 4 is a tube section 18. This tube section is preferably in the form of a coil or helix to further control the flow of the beer to the faucet 3 and has its lower or inlet end 19 adjacent to the bottom of the tank 4 and its upper or outlet end 20 connected into the passage 13 in the boss 11. The diameter and length of the coil 18 is such as to sufficiently retard the speed of the flow under the pressure within the keg to effectuate a controlled discharge at the faucet 3. In practice, the diameter of the coil 18 is relatively smaller than the diameter of the cooling coil 2.

As detailed in Fig. 2, the passage 13 extends to the outer end of the boss 11 which at this end is enlarged and internally threaded for connection with the adjacent threaded end of the shank 5. The latter seats against a shoulder within the shank, there being a rubber gasket 21 between the parts to seal the joint as shown. Located within the shank 5 is a tube element 22. The latter extends completely through and beyond the opposite ends of the shank 5 and abuts against a rubber gasket 23 located within the boss 11 when the parts are clamped together as shown in Fig. 2. Here, the passage 13 has an enlarged section 13a to receive the adjacent end of the tube 22 and mount the gasket 23 at the end thereof. The tube element 22 has a diameter less than the inside diameter of the section 5 to provide a longitudinally extending passage 24 between them. The tube 22 carries a smaller tube 25 as a continuation thereof within the boss 11 in the passage section 13a. The tube 25 extends through the gasket 23 and seats against

a shoulder 26 between the passage 13 and its connected section 13a. The tube 25 is enlarged at its outer end to abut the shoulder 26 and also to provide a seat for the gasket 23 as shown.

The cover casting 9 is provided at one side of the coil 18 with a passage or port 27. This port serves to connect the upper end of the tank 4 with the boss passage 13a about the outer side of the tube element 22. Here, the tube element 22 is reduced in diameter as at 28 to connect the port 27 with the passage 24 between the tube 22 and the shank 5. This port 27 is concerned with the atomizing action of the faucet 3 to control the amount and character of the foam which is placed on the beer which is drawn into the glass or other dispensing container from the faucet 3. The upper end of the tank 4 is divided from the port 27 by a partition wall and check valve mechanism to be later described.

As heretofore stated, the shank 5 extends through and beyond the box wall 1 to the front side thereof and is provided at or adjacent to its end with a flange 29 for a union nut 30 which connects the faucet 3 to the outer end of the shank 5 and clamps the tube 22 against the gasket 23 as shown in Fig. 2. The faucet 3 has a tubular extension 31 threaded on its outer side for engagement by the union nut 30. A gasket 32 is interposed between the flange 29 and the extension 31 to provide a leakproof joint. The outer end of the tube 22 is threaded and screws into the extension 31 at 33, whereby the drawing action of the union 30 on the faucet 3 will clamp the tube 22 against the gasket 23 and the tube 25 against the shoulder 26 to seal the joints in this part of the assembly.

The faucet 3 is preferably in the form of a casting having an outside body or case 34 providing a longitudinally disposed liquid receiving chamber 35 therein. The upper end of this chamber is closed by a screw plug or cap member 36 which has a tubular portion 37 extending into the chamber and in screw threaded connection therewith as shown in Fig. 2. The body 34 of the faucet has a pair of passages 38, 39, one connecting the tube 22 with the lower end of the chamber 35 and the other connecting the passage 24 with the upper end of said chamber. The connection of the passage 39 with the upper end of the chamber 35 is through a number of radial ports 43 in the cap extension 31. These ports open into an annular groove 41 in the cap extension 31 to connect the passage 39 with the ports in any rotative position of the cap element 36 when seated against the faucet body.

Located within the faucet chamber 35 is a valve carrier 42 shaped to have a body wall 43 and spaced, but parallel, cross-members 44, 45. The mechanism to be presently described to open the valve members, also to be later described, is located in the space between the cross-members 44, 45. The wall member 43 of the carrier 42 conforms to and has a loose sliding fit within the chamber 35 as shown in Fig. 4. The carrier 42 is not as long as the chamber 35 and hence may be slid endwise thereof to open and to close a main valve member 47 to be next described.

The valve member 47 is at the lower end of the carrier 42 and cooperates with a valve seat 48 provided within the faucet housing 34 between the chamber 35 and the discharge spout 49 of said housing. The valve member 47 is resilient, being preferably of rubber, to close the connection between the spout 49 and the chamber 35

when the valve member is pressed against its seat 48. A coiled expansion spring 50 within the cap 36 performs this function. This spring normally presses the carrier 42 downwardly having bearing at its lower end on the cross-member 44 and at its upper end against the cap 36. The cross-member 44 carries a boss or projection 51 to center the spring.

To lift the valve member 47 from its seat 48, I provide a manually operable turning arrangement comprising a shaft 52 journaled in the side walls of the faucet housing 34 and provided intermediate its ends with a cam projection 53 between the cross-members 44, 45 as shown in Figs. 2 and 4. The cam projection 53 is located directly beneath the upper cross-member 44 and when raised or rocked upwardly will lift the valve member 47 from its seat 48. Turning the shaft 52 in the opposite direction lowers the projection 53 and the spring 50 closes the valve member 47.

The shaft 52 is mounted in a packing structure 54 where it extends out of the valve housing as shown in Fig. 4, and is equipped at its outer end with an operating handle 55 having at its upper end a suitable grasping knob 56 as shown in Fig. 1. To open the valve 47, the handle 55 is drawn forwardly, that is, towards the operator in the direction indicated by the arrow *a* in Fig. 2. To close the valve member 47 the handle is moved in the reverse direction and the valve member is seated when the handle member 55 reaches a substantially upright position as shown in Fig. 1.

To control the foaming of the beer, I provide the following mechanism.

An atomizing tube 57 is secured to the lower end of the valve carrier 42. This tube is preferably centrally located with respect to the valve member 47 and extends through and below the same into the nozzle 49 as shown in Fig. 2. The tube 57 is provided with a flow passage 58 of relatively small diameter closed at its upper end within the valve 47 by an end wall 59. Here the tube 57 is provided with a number of relatively small, radial apertures or openings 60 which connect the flow passage 58 of the tube with a chamber 61 for the liquid in the faucet housing above the valve 47. The tube 57 is open at its lower end and discharges into the flow passage 62 which the nozzle 49 provides below the valve 47. It will be noted that the tube 57 is smaller in diameter than the nozzle 49 so that both the valve 47 and the tube 57 may respectively discharge the liquid controlled thereby into said nozzle, the discharge from the valve 47 being about the tube. The chamber 61 which is at the upper end of the tube 57 is located within a fixture 63 having a valve seat 64 for a supplemental valve member 65, also of rubber or other desired cushion and sealing material.

The fixture 63 is in the form of a body element having a tubular projection 66 extending into the valve carrier 42 below the cross-member 45 and threaded connected with said carrier. The projection 66 provides a chamber 67 above the valve seat 64 and houses a coiled expansion spring 68 which normally closes the valve member 65 against its seat 64. The chamber 67 connects with the passage 61 when the valve member 65 is opened and liquid entering the faucet chamber 35 through the passage 39 flows into the tube 57 for atomization thereby within the nozzle 49. The pressure of the gas on the beer forcibly dis-

charges it from the tube 57 and due to the small diameter of the tube passage 58 and the ports 60, the liquid stream is broken up in a manner for discharge from the outer end of the tube 57 in an atomized spray. This allows the occluded gases within the liquid to form a rich, creamy foam which on discharge from the nozzle 49 produces the desired collar on the solid column of beer first discharged into the drinking glass or other container from the faucet 3. It is to be understood, that the glass is first filled with solid beer through the main valve member 47, the supplemental valve member being closed at this time by its spring 68.

The valve member 65 is carried by a valve stem 69 within the spring 68 and extending at its upper end into the space between the cross-members 44, 45, through an enlarged opening 70 in the cross-member 45. The upper end of the valve stem 69 is headed as at 71, and this head has tapered walls as shown. A lever 72 engages the head 71 and has a fulcrum projection 73 on its under side to engage the cross-member 45. The lever 72 is fashioned to normally stand at an angle or incline when the supplemental valve 65 is closed as shown in Fig. 2. The downward pressure of the spring 68 on the valve 65 normally holds the lever 72 in this position with its fulcrum projection 73 seated against the cross-wall 45.

The wider end of the lever 72 is in the path of the cam projection 53 and when the shaft 52 is turned to force said projection against the lever the latter is rocked upwardly to lift the valve member 65 from its seat 64. To accomplish this, the handle member 55 is swung away from the operator, the direction being indicated by the arrow *b* in Fig. 2.

The partition wall heretofore referred to is shown at 74 in Fig. 2. This wall member extends across the top of the tank 4 and divides the tank from the port 27. The cover element 9 is fashioned to extend above the tank to provide a chamber 75 above the partition wall 74. The tubes 16 and 18 extend through the partition wall 74 to reach their respective passages 12, 13 in the cover element 9 as shown. These tubes have a sufficiently tight fit in the partition wall 74 so that the liquid in the tank below the partition wall is prevented from flowing into the chamber 75 except through the non-return check valve element 76. The partition wall 74 has a port 77 extending therethrough to connect the portions of the tank 4 on opposite sides of the partition wall and to mount the valve element 76. The latter is self closing being gravity and pressure controlled and when closed seats against a tapered seat about the upper edge of the port opening 77. The head of the valve 76 is tapered to conform to this seat and is located within the chamber 75 so that any increase in pressure within said chamber will close the valve and prevent turbulence or agitation of the liquid content of the tank 4 below the partition wall. With the faucet 3 and the adjoining portion of the shank 5 at room temperature, being out of the cooling influence of the refrigerant within the coil box, there is the likelihood of the gas pressure within the faucet being increased due to the higher temperature to which the faucet and the shank are exposed. The check valve 76 closes off the tank 4 from this increase in pressure on the foam providing side of the apparatus and no objectionable reaction occurs on the liquid within the tank 4 below the partition wall 74 to disturb the

drawing of a solid column of beer from the tank through the main valve 47. On this side of the apparatus the retarding influence of the coil 18 within the tank 4 lessens the opportunity of this increase of pressure within the faucet and the shank disturbing the liquid content of the tank with which the coil connects. If desired, a check valve, as shown in Fig. 7, may be incorporated in the flow line between the tank 4 and the main valve 47. The structure disclosed in Fig. 7 will be described later.

The check valve 76 has the further advantage of reducing the possibility of gurgling at the faucet 3 on opening the supplemental valve 65. This is due to the fact that free gas is not so likely to collect because of the liquid column which these valves when closed confine between them.

The check valve 76 has a dependent stem 78 extending through the port 77 into the tank 4. This stem has a sliding fit within the port to guide the valve 76 in its opening and closing movements. A cotter pin 79 or other equivalent stop is carried by the stem 78 below the partition wall 74 to limit upward movement of the valve 76 and prevent its displacement from the port 77 during the handling as well as the operation of the device.

As before stated the flow of liquid from the tank 4 to the portion of the faucet 3 above the valve 47 is through the port 27 and the connected passage 24. When the supplemental valve 65 is open the liquid may flow from the tank 4 into the faucet through the port 27 due to the pressure of the incoming liquid raising the valve and the reduction of pressure on the upper side of the valve. When the supplemental valve is closed, the check valve 76 closes by the pressure of the liquid column thereon aided by gravity, the valve 76 operating vertically as shown. I might remark at this point that the stem 78 of the check valve 76 is grooved longitudinally so that the liquid may flow past the valve into the chamber 75 when the check valve is raised. Any increase in pressure within the liquid column between the faucet and the chamber 75 will, as before stated, act on the valve 76 and keep it closed.

The mechanism shown and so far described operates as follows: After the cooling coil 2 has been connected with the keg, the pressure within the keg will fill the system with liquid up to the valves 47 and 65. The latter are closed at this time and the system is ready for use as shown in Figs. 1 and 2. To dispense a quantity of beer, the handle 55 is drawn forwardly and a solid flow of beer is discharged from the faucet 3 into the receiving glass or other receptacle without agitation due to the control as afforded by the tank 4 and the coil 18. When the receiving receptacle has been filled to the desired extent, as for example up near the top, the flow of solid beer is cut off by the operator returning the handle 55 to its upright position as shown in the drawings to close the main valve 47. The small amount of agitation produced within the beer as it is discharged into the glass will not create much of a foam on the top of the column. To add the desired foam or collar, the operator moves the handle member 55 rearwardly in the direction of the arrow b in Fig. 2 to open the supplemental valve 65. The beer is now atomized by the tube 57 and a creamy and relatively thick foam is deposited on the solid beer in the receiving receptacle. This enhances the appear-

ance and improves the taste of the beverage. Returning the handle 55 to its upright position closes the valve 65 and the apparatus is ready for the next draw.

When applying my invention to a direct draw system the structure is constructed as shown in Fig. 5. Here 80 indicates a tap rod assembly the lower portion 81 of which is inserted into the keg through a suitable tapping fixture not shown. The lower portion 81 constitutes in effect the tap rod for the assembly and is comprised of an outer tube 82 and an inner tube 83. These tubes are of different diameters and are arranged one within the other to provide an annular liquid flow passage 84 therebetween. A plug element 85 closes the lower ends of both tubes and is provided with a series of radially disposed inlet ports or openings 86 which connect the interior of the keg to the inner tube 83. The upper end of the latter is connected with the flow passage 84 in any suitable manner, the particular arrangement shown in Fig. 5 constituted in having the upper end of the inner tube 83 terminating short of the upper end of the outer tube 82. In this way liquid flowing into the inner tube 83 at its lower end may flow into the passage 84 for entry into the main draft tube 87 which extends into the passage 84 from a head casting 88 at the upper end of the draft rod assembly as shown in Fig. 5. A cylindrical member 89 connects the head 88 to the tap rod section 81 and provides a liquid receiving chamber 90 therebetween. The tube 87 extends through the chamber 90 and has its upper end extending into and having a tight fit in a passage 91 in the head 88. This passage 91 opens into a joining passage 92 which corresponds to the passage 13 in the faucet structure 3 of Fig. 2. The passage 92 supplies liquid to a tube element 22a embodied in the faucet device 3a and serving the same purpose as the tube 22 in the faucet 3.

The head 88 has another passage 93 serving the same purpose as the port 27 of the device shown in the previous figures and this passage 93 connects at its lower end with the chamber 90 and at its upper end with a passage 24a in the faucet device 3a. The passage 24a serves the same purpose as the passage 24 in the faucet 3. To prevent an increase in pressure in the liquid column between the faucet 3a and the chamber 90 disturbing the liquid column within the tap rod section 81, I provide a check valve arrangement at the lower end of the chamber 90 as shown in Fig. 5. This check valve arrangement serves the same purpose as the check valve device heretofore shown and described and is constructed as follows:

The device comprises a partition wall 94 which divides the chamber 90 from the upper end of the inner and outer tube assembly of the tap rod section 81. The partition 94 is supported above the upper ends of this tube assembly by a coupling element 95. The latter not only supports the partition wall 94, but connects the upper end of the outer tube 82 with the member 89. A self closing check valve 96 is mounted in the partition wall 94 at a port 97 in the same manner as shown in the previous figures. This check valve 96 is located to one side of the tube 87 which extends through the partition wall 94 with a sufficient tight fit to prevent liquid flowing into the chamber 90 except through the check valve as before. This check valve has a grooved stem 98 which guides the check valve in its opening and closing movements and also provides for the

flow of liquid through the partition wall when the check valve is open. The check valve also has a stop pin 99 as shown.

In the arrangement shown in Fig. 5, the flow of liquid to the selectively operable main and supplemental valves is through the passages 91 and 93, respectively. When the main valve is opened the flow is through the tube 87 and a solid column of liquid is discharged from the faucet 3a. When the supplemental valve is opened the liquid is discharged in atomized form at the faucet tube 57 as before.

Another feature of my invention which is important is this: It will be noted in Fig. 2 that the faucet chamber 35 extends below the seat 48 for the main valve 47 and that the supply passage 33 for the beer enters the lower end of the chamber 35 in the region of this valve seat. It will also be noted that the valve member 47 is smaller in diameter than the chamber 35 and provides a space about said valve member. Above this space or above the valve member 47 is a cup-packing 100 of rubber. This packing engages the wall of the chamber 35 above the main valve and has a tapered, upright flange 101 which surrounds the fixture 63 to provide a space 102 for beer under pressure to enter into and press the cup-rubber into sealing contact with the faucet body. This cup-packing 100 divides the chamber 35 into the upper and lower sections, the lower to supply the main valve 47 and the upper to supply the supplemental valve 65. In this way the opening of one valve does not deplete the supply for the other. Moreover, the arrangement enables the free gases collecting under the valve member 47, when closed, to escape into the nozzle 49 in advance of the beer stream on opening the valve 47. In this way agitation of the beer at each initial draw is prevented and excessive or undesired foaming in the glass is avoided. It is to be understood that the faucet 3a in Fig. 5 will be constructed the same as the faucet 3.

As shown herein the valve members 47, 65 are arranged one within the other, and one is carried by the other. It will be further noted that the liquid is discharged from the supplemental valve 65 through the main valve 47. These factors not only simplify the faucet structure, but contribute to its compactness as required for a unitary dispensing fixture. This feature of compactness is further brought about by having the carrier 42 supporting both valve systems. In addition, this arrangement provides for the opening of the main valve 47 by direct action of the actuating mechanism on the carrier itself, leaving the supplemental valve closed and for an opening movement independently of the main valve or the carrier. In closing, I may remark that the beer conveying conduit which carries the beer from the source of supply to the faucet includes the coil 3, the shank 5 and all of the other passage providing means herein disclosed to carry the beer to the faucet for discharge therefrom. The carrier 42 has a sufficiently loose fit within the faucet chamber 35 for the flow of liquid to the flange 101 of the cup-rubber 100 to press said flange against the chamber wall. Also, the opening 70 in the cross-member 45 is large enough to provide a flow passage to the supplemental valve 65. The upper end of the tank 4 has a leak-proof connection with the cover element 9 and the latter supports the tank from the shank section 5 of the faucet device.

The check valve assembly 103 shown in Fig. 7 comprises a valve member 104 and a seat therefor

in the form of an insert 105 in the cover casting 9 at the passage 13 above the coil 18. The valve 104 has a stem 106 which extends into a guide bore 107 within a plug 108 which is screwed into the cover 9 in the top of the opening with which the cover is provided to accommodate this valve. The valve member 104 is arranged for vertical operation and closes the coil 18 from the faucet on an increase of liquid pressure therein. On reducing the pressure, as on opening the main valve 47, the check valve 104 is raised by the liquid flow into the passage 13. If desired, a check valve may be incorporated in the flow passage 91 in the direct draw system shown in Fig. 5.

In Fig. 8 I have shown a glass or other drinking container c into which beer is drawn from my improved faucet device. The column of solid beer, which fills the glass to a point up near the top is marked d. The layer of foam or collar which is deposited into the glass on top of the solid beer from the supplemental valve 65 is marked e. This collar e, as heretofore pointed out, is composed of a rich creamy foam and provides, so to speak, an insulating blanket on top of the solid beer in the glass. This blanket e, seals in the gas content within the solid beer in that the insulating characteristics of the rich creamy collar prevents the microscopic gas bubbles which rise to the top of the column of solid beer from enlarging and escaping as in an ordinary glass of beer drawn from the conventional faucets. These microscopic bubbles are retained on the top of the solid beer in a layer as indicated at f in Fig. 8 and the taste and flavor of the beer in the glass is preserved throughout the drinking period. Inasmuch as the collar e follows down with the solid beer as its level lowers in drinking from the glass, the microscopic bubbles are not allowed to enlarge and escape and the taste and flavor of the beer is retained.

The details of construction and arrangement of parts shown and described may be variously changed and modified without departing from the spirit and scope of my invention, except as pointed out in the annexed claims.

I claim as my invention:

1. In a dispensing apparatus of the character described for a carbonated beverage having inlet and discharge openings, relatively movable main and supplemental valve means interposed between said openings, the main valve means controlling a solid flow of liquid to the discharge opening, the supplemental valve means controlling an atomized flow of the liquid to the discharge opening, said supplemental valve means being carried by and discharging through the main valve means and remaining closed during the opening and closing movement of the main valve means, and manually operable means for selectively actuating said valve means, said actuating means having co-acting elements, one for opening the main valve means and the other for opening the supplemental valve means.
2. In a dispensing apparatus of the character described for a carbonated beverage having inlet and discharge openings, relatively movable main and supplemental valve means interposed between said openings, the main valve means controlling a solid flow of liquid to the discharge opening, the supplemental valve means controlling an atomized flow of the liquid to the discharge opening, said supplemental valve means being carried by and discharging through the main valve means and remaining closed during

the opening and closing movement of the main valve means, and co-acting cam and lever elements for manually and selectively opening the respective valve means.

3. In a dispensing apparatus of the character described for a carbonated beverage having a liquid receiving chamber and inlet and discharge openings connected thereto, a carrier slidably mounted within said chamber and having spaced cross-members, main and supplemental valve means supported by said carrier for controlling the flow of liquid from the chamber to the discharge opening, the main valve means controlling a solid flow of liquid to said discharge opening, the supplemental valve means controlling an atomized flow of liquid to said discharge opening, and manually operable co-acting cam and lever elements located in said chamber between said cross-members for selectively opening said valve means, the cam element acting in the carrier through one cross-member and the lever element having support on the other cross-member for action on the supplemental valve means.

4. In a dispensing apparatus of the character described for a carbonated beverage having a liquid receiving chamber and inlet and discharge openings connected thereto, main and supplemental valve means located within said chamber for controlling the flow of liquid therefrom to said discharge opening, the main valve means controlling a solid flow of liquid from the chamber to the discharge opening, the supplemental valve means controlling an atomized flow of liquid from the chamber to said discharge opening, and manually operable means located in said chamber for selectively opening said valve means, said chamber having a seat therein for the main valve means spaced from the discharge opening for venting the accumulated gas ahead of the liquid on opening the main valve means.

5. In a dispensing apparatus of the character described for a carbonated beverage, a dispensing faucet having an inlet and a discharge, a liquid conveying conduit connected to said faucet at said inlet, said conduit having a section at the faucet provided with a pair of separate passages to divide the liquid flowing into the faucet from the conduit into separate streams, relatively movable main and supplemental valve means in the faucet for controlling the discharge of the liquid from the faucet from the respective streams, the supplemental valve means discharging through said main valve means, and an atomizing tube connected to the supplemental valve means for atomizing the stream discharged from the faucet from the supplemental valve means.

6. In a dispensing apparatus of the character described for a carbonated beverage, in combination with a coil box, a liquid conveying conduit and a dispensing faucet therefor located within and outside of the box, respectively, said faucet having an inlet and a discharge, a tubular shank member extending through the box and connecting the conduit to the faucet at the inlet of the latter, a tube element located within and extending through said shank member to provide for the flow of liquid through the shank member to the faucet in divided paths, and relatively movable main and supplemental valve means within the faucet for controlling the discharge therefrom of the liquid from the respective paths, said supplemental valve means discharging through the main valve means, manually operable means for selectively opening said valve

means, and an atomizing device connected with the supplemental valve means for atomizing the flow of liquid therefrom.

7. In a dispensing faucet of the character described for a carbonated beverage having a liquid receiving chamber and a discharge nozzle containing a discharge passage connected to said chamber, main valve means and a seat therefor located within the chamber and controlling a solid flow of liquid from the chamber to said nozzle, a tube element extending into the nozzle from the main valve means and carried thereby, said tube element having one or more apertures connecting the tube with said chamber to promote the atomization of the liquid discharged from the tube into the nozzle, supplemental valve means and a seat therefor carried by the main valve means within the chamber for controlling the flow of liquid from the chamber to the tube, and manually operable means for selectively actuating said main and supplemental valves.

8. In a dispensing faucet of the character described for a carbonated beverage having a liquid receiving chamber and a discharge nozzle containing a discharge passage connected to said chamber, main valve means and a seat therefor located within said chamber and controlling a solid flow of liquid from the chamber to the nozzle, a tube element extending into the nozzle from the main valve means and carried thereby, said tube element having one or more apertures connecting the tube with the chamber to provide for the atomization of the liquid discharged from the tube into the nozzle, supplemental valve means and a seat therefor carried by the main valve means within the chamber for controlling the flow of liquid from the chamber to the tube, co-acting cam and lever elements located within the chamber for selectively opening the main and the supplemental valves, spring means for biasing said valves to their closed positions, and manually operable control means carried by the faucet body for actuating said cam and lever elements.

9. In a dispensing faucet of the character described for a carbonated beverage having a receiving chamber and a discharge nozzle containing a discharge passage connected to said chamber, a carrier movably mounted within the chamber by sliding contact with the surrounding wall thereof, main and supplemental valve means supported by the carrier, the main valve means controlling a solid flow of liquid from the chamber to the nozzle, a tube element connected with the chamber through the main valve means and carried by said carrier, said tube element extending into the nozzle from the carrier to atomize the liquid discharged from the tube into the nozzle, the supplemental valve means controlling the flow of liquid from the chamber to the tube, manually operable means for selectively opening the respective valve means, and spring means mounted on the carrier for biasing the valve means to their closed positions.

10. In a dispensing faucet of the character described for a carbonated beverage having a liquid receiving chamber and a discharge opening connected thereto, a carrier slidably mounted within said chamber and dividing the same into upper and lower sections, main and supplemental valve means supported on the carrier for controlling the flow of liquid from the respective chamber sections to the discharge opening, the main valve means controlling a solid flow of liquid from the lower section of the chamber, the supplemental valve means controlling an atomized flow of liquid

from the upper section of the chamber, said faucet having liquid inlets for separately furnishing liquid to the chamber sections, and manually operable means for selectively opening said valve means.

11. In a dispensing apparatus of the character described for a carbonated beverage, a liquid receiving chamber divided into upper and lower sections, a dispensing faucet having separate passages respectively connected with the upper and the lower sections of said chamber, valve means in said faucet for the selective discharge of liquid from said passages, and a non-return check valve for controlling the flow of liquid from the lower to the upper section of said chamber, said check valve closing on an increase of pressure within the upper section of the chamber.

12. In a dispensing apparatus of the character described for a carbonated beverage, a liquid receiving settling tank and a dispensing faucet connected in series relation, a partition wall dividing said tank into upper and lower sections, said faucet having separate passages respectively connected with the upper and the lower sections of said tank, valve means in said faucet for the selective discharge of liquid from said passages, a port in the partition wall for the flow of liquid from the lower to the upper section of the tank, and a non-return check valve for said port, said check valve closing in response to an increase of pressure within the upper section of the tank to prevent turbulence of the liquid content of the lower section of the tank.

13. In a dispensing apparatus of the character described, a liquid receiving chamber divided into upper and lower sections, a dispensing faucet having separate passages respectively connected with the upper and lower sections of said chamber, valve means in the faucet for the selective discharge of liquid from said passages, and non-

return check valves, one in each of said passages, for controlling the flow of liquid to the faucet from the respective sections of the chamber, said check valves closing on an increase of pressure of the liquid within the respective passages at the faucet.

14. A dispensing faucet of the character described for carbonated beverages, comprising a body and a connected discharge spout having a liquid flow passage extending therethrough with an inlet section within the body and an outlet section within the spout, a valve seat within the body between the inlet and the outlet sections of said flow passage, relatively movable main and supplemental valve members mounted within the body adjacent to said seat, the main valve member co-operating with said seat for controlling a solid flow of liquid through the flow passage from the inlet section to the outlet section thereof when the main valve member is opened, said main valve member having a seat and a flow passage opening therethrough from the inlet to the outlet sections of said main flow passage and having an atomizing port on the discharge side of said last named seat, the supplemental valve member being carried by the main valve member and cooperating with the seat thereon for controlling an atomized flow of liquid through the main valve member to the spout when the supplemental valve member is opened, spring means acting on the supplemental valve member to keep the latter closed while the main valve member is closed and during the opening and closing movement of the main valve member, and manually operable means having a single handle member extending upwardly from the body and accessible from above the valve members for selectively actuating the valve members to opened positions.

THOMAS A. NIGBOR.
